UNITED STATES PATENT OFFICE.

RILEY C. BOTT, OF GROUSE, OREGON.

RAIL-JOINT.

SPECIFICATION forming part of Letters Patent No. 747,037, dated December 15, 1903.

Application filed July 18, 1903. Serial No. 166,112. (No model.)

To all whom it may concern:

Be it known that I, RILEY C. BOTT, a citizen of the United States, residing at Grouse, in the county of Wallowa and State of Oregon, have 5 invented new and useful Improvements in Rail-Joints, of which the following is a specification.

This invention relates to rail-joints, the object in view being to provide a simple, reliable, and effective joint for the meeting ends of the rails of a railway which will prevent the lateral or vertical bending of the rail ends at the point where the joints occur.

A further object of the invention is to construct the splice-bars or fish-plates in such manner that they may be readily applied to and removed from the rails and interlock with the rails both at the head and base when in their applied positions.

20 With the above general objects in view the invention consists in the novel construction, combination, and arrangement of parts, as hereinafter fully described, illustrated, and claimed.

25 In the accompanying drawings, Figure 1 is a perspective view of a rail-joint constructed in accordance with the present invention. Fig. 2 is a vertical longitudinal section through one of the fish-plates or splice-bars. Fig. 3 is a side elevation of two rail ends, showing the detachable key. Fig. 4 is a vertical cross-section through the rail-joint, taken in line with one of the bolts. Fig. 5 is a detail perspective view of the key.

30 Like reference-numerals designate corresponding parts in all the figures.

In carrying out the present invention I make use of a pair of fish-plates or splice-bars, each of which is composed of two sections 1 and 2, pivotally connected or hinged together about centrally of their height. The upper and lower sections of each fish-plate or splice-bar are provided with interfitting knuckles 3, while all the knuckles are provided with longitudinally-extending and registering openings for the reception of a hinge-pin 4, which extends practically the entire length of the fish-plate, as shown in Fig. 2, and enables the two members of the fish-plate 45 to be rocked relatively to each other.

The upper member 1 is provided along its

upper edge with upstanding dowels or projections 5, while the lower member is provided along its lower edge with downwardly-extending dowels or projections 6. The head of the 55 rail is provided with sockets or recesses 7 to receive the projections 5, and the base of the rail is provided with sockets or openings 8 to receive the projections 6, so that when the fish-plates are in position a positive interlocked engagement is had between said fish-plates and the head and base of the rail ends. Two of such fish-plates or splice-bars are employed and located at opposite sides of the rail, so as to bear against the web of the rail, 65 and they are held in place by two or more bolts 9, which extend through the fish-plates and web of the rail and are arranged so as to dodge the hinge-pins 4, as shown in Fig. 2.

The meeting ends of the rails are recessed 70 correspondingly to receive the opposite ends of a key 10, as shown in Figs. 3 and 4, said key comprising a parallel-sided central portion 11, the tapering end portions 12, and the disk-shaped extremities or heads 13. The 75 rail ends are recessed to loosely receive the end portions of the key 10, which acts to prevent breaking down of the joint and also prevents undue separation or moving apart of the ends of the rail. The key is inserted in 80 the plates before the fish-plates or splice-bars are applied, the latter preventing the displacement of the key when in position.

In order to remove the fish-plates, the bolts are first extracted, and then by means of a 85 suitable pry or lever applied midway the height of the fish-plates the latter are broken outward along the line of their hinged connection, thus withdrawing the dowels or projections from their sockets in the base and 90 head of the rail and permitting the fish-plates to be entirely removed.

Having thus described the invention, what I claim as new, and desire to secure by Letters Patent, is—

1. A rail-joint comprising a pair of fish-plates, each composed of two members provided with interfitting knuckles connected by a hinge-pin extending lengthwise of the members, bolts for securing the fish-plates to 100 the rail ends, one or both of said members being provided with projections which are

received in sockets in the rail ends, substantially as described.

2. A rail-joint comprising rail ends having the web portions thereof recessed, a key re-
5 movably fitted in said recess and serving to prevent excessive endwise movement of the rails, and fish-plates secured to the opposite sides of the rail ends and acting to prevent

the displacement of the key, substantially as described.

In testimony whereof I affix my signature in presence of two witnesses.

RILEY C. BOTT.
